(57) CLAIM

The ornamental design for a bottle, as shown and described.

DESCRIPTION

FIG. 1 is a front perspective view of the bottle according to the present design;

FIG. 2 is a side detailed view of a bottom section of the bottle of FIG. 1; and,

FIG. 3 is a bottom view of the bottle according to the present design.

The broken lines shown in FIGS. 1 and 2 are illustrative of a depression located in the bottom of the bottle.

The broken lines in FIG. 3 are illustrative of the ridge around the bottom of the bottle.
